CLAIM

We claim the ornamental design for a pry bar, as shown and described.

DESCRIPTION

This document is a reissue of U.S. Design Pat. No. D. 821,843, which granted on Jul. 3, 2018, from U.S. Design patent application Ser. No. 29/590,661, filed on Jan. 12, 2017, the entire contents of which are hereby incorporated by reference herein.

FIG. 1 is a perspective view of a pry bar according to an embodiment of the invention.

FIG. 2 is a first side view of the pry bar shown in FIG. 1. FIG. 3 is a second side view of the pry bar shown in FIG. 1.

FIG. 4 is a first end view of the pry bar shown in FIG. 1. FIG. 5 is a second end view of the pry bar shown in FIG. 1. FIG. 6 is a third side view of the pry bar shown in FIG. 1. FIG. 7 is a fourth side view of the pry bar shown in FIG. 1. FIG. 8 is a perspective view of a pry bar according to another embodiment of the invention.

FIG. 9 is a first side view of the pry bar shown in FIG. 8. FIG. 10 is a second side view of the pry bar shown in FIG. 8.

FIG. 11 is a first end view of the pry bar shown in FIG. 8. FIG. 12 is a second end view of the pry bar shown in FIG. 8.

FIG. 13 is a third side view of the pry bar shown in FIG. 8; and, FIG. 14 is a fourth side view of the pry bar shown in FIG. 8.

The broken lines depict portions of the pry bar in which the design is embodied that are not considered part of the claimed design. Any broken lines having unequal line segments indicate the boundary of the claimed design.
